CLAIM

The ornamental design for a dielectric boot, as shown and described.

DESCRIPTION

FIG. 1 is a perspective view from the instep side of the boot; FIG. 2 is a side elevation view of the side of the boot opposite from the instep; FIG. 3 is a side elevation view of the instep side of the boot; FIG. 4 is a front view of the boot; FIG. 5 is a rear view of the boot; FIG. 6 is a top plan view of the boot; and, FIG. 7 is a bottom view of the boot.

In FIGS. 1-7, the broken lines depict environmental or contextual subject matter only and form no part of the claimed design.
